UNITED STATES PATENT OFFICE

WILLIAM F. SCHERER, OF KANSAS CITY, MISSOURI

COMBINATION COLLAR BUTTON AND TIE HOLDER

Application filed August 4, 1930. Serial No. 472,863.

The present invention relates to collar and tie fastening devices, and aims to provide a simple two-piece article adapted to serve both as a permanent mounting for the tie and also as a means for fastening the tie as well as the collar to the neck band of the shirt.

It is also an object of the invention to provide a device of this character which will enable the tie to be attached in wearing position by a practically instantaneous movement, and also permit of a certain degree of adjustment of the tie into fastened position.

It is a further object of the invention to provide a novel device in this class of fastening devices, one important feature of which is its construction whereby it serves to prevent any turning movement of the tie out of proper wearing position.

With the foregoing general objects in view, the invention will now be described by reference to the accompanying drawings illustrating a practical and serviceable construction for embodying the proposed improvement, after which those features and combinations deemed to be novel will be particularly set forth and claimed.

In the drawings—

Figure 1 is a perspective view of the collar button portion of the device, including its shank portion;

Figure 2 is a similar view of the other portion of the device, which serves as a tie mounting;

Figure 3 is a perspective view of said two parts in assembled relation;

Figure 4 is a plan view illustrating a bow tie with the tie mounting member partly secured thereto, but with the middle band portion of the tie left unsecured;

Figure 5 is a similar view, but showing the middle band portion of the tie completely secured in permanent position; and

Figure 6 is a sectional detail, illustrating the fastening device in operative position for securing a bow tie to the neck band and collar of the shirt.

Referring now to said drawings in detail, this illustrates my improved device as comprising a collar button element 6 provided with a resilient shank portion made up

of suitable flat spring material 7 (such as metal or celluloid), looped or folded, so as to provide a resiliently expansive construction, as represented in Figure 1. For the tie mounting member of the device, I provide a flat tubular element 8, of similar resilient material, for frictional telescoping engagement with the shank portion 7 of the first member, and thus adapted to be secured in any desired adjusted position thereon.

One end of the element 8 is formed with a set of transverse lugs or flanges 9, and its other end is formed with a pair of lip flanges 10 for engagement with the collar tabs 12 when pressed into wearing position, as represented in Figure 6.

In attaching the tie 14 to the tie mounting member, the rear middle portion 15 of the tie is placed flat against the lugs 9 and then stitched thereto as indicated at 16 in Figure 4; then the bow band 17 is folded over at both ends against the opposite sides of the tubular portion 8, and likewise stitched to the lugs 9, as indicated at 18 in Figure 5. By this means, I secure a mounting structure in which the flat tubular element 8 is in alignment with the main horizontal or longitudinal dimension of the tie 14, so that when the mounting is slipped over the shank 7, there is no opportunity for rotative movement afforded the tie or its mounting, and it is thereby kept from turning in either direction out of its proper horizontal or wearing position.

This is assured by the further fact that the shank 7 is inserted flatwise through the usual horizontal slits 20 provided as button holes in the neck band 21 and the collar tabs 12 (see Figure 6).

It will thus be seen that the tubular element 8 is constituted as a permanent tie mounting for the tie, and that the only operation required for attaching the tie in wearing position is to fit the part 8, by a substantially instantaneous movement, over the shank portion 7 of the collar button member. The frictional gripping action between the parts 7 and 8, when thus telescoped, is adequate for preventing any casual detachment of the tie from wearing position, in ordinary

use. Moreover, the tubular element 8 is open at both ends, permitting the shank 7 of the collar button member to be projected entirely through the tubular element 8, or to 5 whatever extent the wearer desires, according to how snugly he wishes to fasten the parts. This provides an adjustable range of attachment, the wearer applying the tubular element 8 constituting the tie mounting to 10 the shank 7 and pushing the part backward until the flange portions 10 engage the collar tabs, after which the wearer can complete the adjustment by pushing the tie and its mounting to whatever further extent he desires, up to the point of compressing the neck band and collar tabs tightly together, as 15 shown in Figure 6. An important feature of the invention is the horizontal flat construction of the shank 7 of the collar button member and the tubular element 8, which insures that the tie will remain permanently in proper horizontal wearing position, since this flat formation, in combination with the straight slits of the button holes 20, prevents 20 any tendency toward rotative movement of either part of the fastener.

The construction comprising a simple two-piece combination, it is apparent that the cost of an article of this type will be extremely low, and the tie mounting portion may be left as a permanent part of each individual tie, and these may be interchangeably mounted upon the shank portion 7 of the collar button.

25 The device is equally well adapted for the bow type of tie illustrated, and for other forms of ties which can be attached to the member 8 with the same facility, and constitute a permanent tie mounting, as above described.

30 It will thus be seen that a practical construction has been provided for carrying out the various desired objects of the invention, including the elimination of troublesome rubber bands, hooks, and other forms of pointed devices for securing a tie in position, and without any sacrifice of the convenience as well as quickness of operation, which characterize my improved form of attaching means to a high degree.

35 While I have illustrated and described what now appears to be the preferred mode of embodying the improvement in practice, I desire to reserve the right to make whatever changes or modifications may fairly fall within the scope of the appended claims.

What I claim is:

40 1. A combination collar button and tie fastener comprising a collar button element having a shank portion formed of flat and bowed spring material, and a flat tubular tie mounting element formed with tie-attaching projections at one end, said tie mounting element having a passage therethrough of a size and shape frictionally and adjustably ac-

commodating said shank portion, said passage through said mounting element being open at both ends to permit projection of said shank entirely through the mounting element and thereby allowing movement of said mounting element into tight fitting relation against the collar.

2. A combination collar button and tie fastener comprising a collar button element having a shank portion formed of a strip or flat spring material folded upon itself intermediate its ends and the latter attached to said button element, and a flat tubular tie mounting element formed with tie-attaching projections at one end and a collar engaging flange at its other end, said tie mounting element having a passage therethrough of a size and shape accommodating the said folded strip of spring material and the latter having oppositely bowed portions for adjustable engagement within said passage, said passage through said mounting element being open at both ends to permit projection of said shank entirely through the mounting element and thereby allowing adjustment of said flange into tight fitting relation against the collar.

In witness whereof I hereunto affix my signature.

WILLIAM F. SCHERER.
